SIDE FRAME FOR A CHAIR OR
SIMILAR ARTICLE

John W. Caldwell, 1829 Warwick Road,
San Marino, Calif. 91108

Continuation-in-part of abandoned design applications Ser.
No. 133,470 and Ser. No. 133,471, both Apr. 12, 1971.
This application Aug. 22, 1973, Ser. No. 390,413

Term of patent 14 years

Int. Cl. D6—06
U.S. Cl. D6—192

FIG. 3

FIG. 2

FIG. 1

FIG. 6

FIG. 5

FIG. 4

FIG. 1 is a view in side elevation of a side frame for a chair or similar article showing my design;

FIG. 2 is a partial front elevation view of FIG. 1;

FIG. 3 is a perspective view of a knuckle portion of the side frame of FIG. 1;

FIG. 4 is a view in side elevation of a modified form of the article shown in FIG. 1;

FIG. 5 is a partial front elevation view of FIG. 4; and

FIG. 6 is a perspective view of a knuckle portion of the side frame of FIG. 4.

This is a continuation-in-part of applicant's co-pending patent applications, Ser. Nos. 133,470 and 133,471, both filed Apr. 12, 1971, and now abandoned.

I claim:

The ornamental design for a side frame for a chair or similar article, as shown.
